his Attorney.

UNITED STATES PATENT OFFICE.

EDMUND J. SCHMIDT, OF CHICAGO, ILLINOIS.

BED-GUARD.

1,333,039.

Specification of Letters Patent.

Patented Mar. 9, 1920.

Application filed July 8, 1918. Serial No. 243,738.

To all whom it may concern:

Be it known that I, EDMUND J. SCHMIDT, a citizen of the United States, and a resident of the city of Chicago, county of Cook, and State of Illinois, have invented certain new and useful Improvements in Bed-Guards, of which the following is a specification.

My invention relates to improvements in bed guards especially adapted to prevent children or ill persons from falling out of the same, and has for its object the provision of an improved construction of this character which is simple and efficient in use, may 10 be readily attached to any bed, and may be readily shifted from position of use into position of nonuse.

Other objects will appear hereinafter.

The invention consists in the combinations 20 and arrangements of parts hereinafter described and claimed.

The invention will be best understood by reference to the accompanying drawing forming a part of this specification, and in 25 which,

Figure 1, is an end view of the bed equipped with guards, embodying the invention,

Fig. 2, a section taken on line 2—2 of 30 Fig. 1, and

Fig. 3, a section taken on line 3—3 of Fig. 1.

The preferred form of construction, as 35 illustrated in the drawings, comprises guard members 4 in the form of longitudinal slats or strips adapted to be secured along the sides of a bed above the normal supporting surface thereof, as indicated. Each of the guard members 4 is surrounded at each end 40 thereof by a strap or band 4', which is preferably longitudinally adjustable thereon. Each of the bands 4' is provided at the bottom with a downwardly extending eyelet 5 pivotally connecting with another eyelet 6, 45 which is rigidly connected with one link of a flexible clamping chain 7 adapted to surround and clamp upon the corresponding bed post, as indicated. One end of the chain 7 carries a perforated ear 8 connected with 50 a corresponding perforated ear 9 by means of an adjusting bolt 10, the ear 9 being equipped with a hook 11 adapted to engage the links of chain 7 to facilitate the adjustment and clamping of the chain around the bed posts of various sizes and shapes, as will 55 be readily understood. At its upper end, each of the straps 4' is provided with an

upwardly extending eyelet 12 pivotally engaging an eyelet 13 swiveled to a flexible strap 14 adapted to embrace the corresponding bed post and being secured thereto by means of a suitable buckle 14'. A guard 15 of leather or other suitable material is arranged over the head of the stud of eyelet 13 to prevent marring of the bed post. 60 65

By this arrangement, it will be observed that one or more of the guard members may be readily attached to beds of different lengths or having bed posts of different sizes or shapes; and that when not in use 70 the guard members may be readily swung downwardly into the positions indicated in dotted lines in Fig. 1, where they will be out of the way but instantly available for re-use. 75

While I have illustrated and described the preferred form of construction for carrying my invention into effect, this is capable of variation and modification without departing from the spirit of the invention. 80 I therefore, do not wish to be limited to the precise details of construction set forth, but desire to avail myself of such variations and modifications as come within the scope of the appended claims. 85

Having described my invention, what I claim as new and desire to secure by Letters Patent is:—

1. A bed guard comprising a guard member adapted to extend along the side of the bed; bands embracing each end of said guard member; and clamps connected with the tops and bottoms of said bands and adapted to embrace the posts of a bed, substantially as described. 90 95

2. A bed guard comprising a guard member adapted to extend on the side of the bed; bands embracing each end of said guard member; eyes extending upwardly from the top and downwardly from the bottom of each of said bands; adjustable clamping chains having eyes pivotally connected with the eyes at the bottoms of said bands; and clamping straps pivotally connected with the eyes at the tops of said bands substantially as described. 100 105

In testimony whereof I have signed my name to this specification in the presence of two subscribing witnesses.

EDMUND J. SCHMIDT.
